UNITED STATES PATENT OFFICE.

CHARLES T. HAM, OF ROCHESTER, NEW YORK.

LAMP-STOVE.

SPECIFICATION forming part of Letters Patent No. 309,713, dated December 23, 1884.

Application filed February 5, 1884. (No model.)

To all whom it may concern:

Be it known that I, CHARLES T. HAM, of the city of Rochester, in the county of Monroe and State of New York, have invented new and useful Improvements in Lamp-Stoves, of which the following is a specification.

This invention relates to an improvement in that class of stoves which are provided with wick-burners adapted to burn kerosene and similar oils, and has for its object to render the air-supply to the burner more steady and uniform than heretofore, to facilitate the exit of the products of combustion, and to improve the means whereby the rear end of the movable top portion of the stove is supported upon the base of the same.

My invention consists, to these ends, of the improvements in the construction of the stove, which will be hereinafter fully set forth, and pointed out in the claims.

In the accompanying drawings, consisting of three sheets, Figure 1 represents a longitudinal vertical section of my improved stove. Fig. 2 is a longitudinal cross-section through the front portion of the stove. Fig. 3 is a rear elevation of the device, whereby the rear end of the top portion is supported upon the base. Fig. 4 is a horizontal section in line $x-x$, Fig. 1. Fig. 5 is a top plan view of the outlet for the products of combustion. Fig. 6 is a vertical longitudinal section, on an enlarged scale, of the lower portion of the stove. Fig. 7 is a sectional elevation of a modified form of my improved stove.

Like letters of reference refer to like parts in the several figures.

A represents the base of the stove, A' the oil-reservoir secured in the same, and a the wick-tubes projecting upwardly from the oil-reservoir.

B represents a closed air-chamber arranged above the oil-reservoir, and inclosing the upper ends of the wick-tubes a.

c represents the elongated burner-cones, which surmount the upper ends of the wick-tubes a, and which are cast in one piece with plates C. The latter are seated in openings in the top plate, b, of the air-chamber B.

D represents the flame-chambers arranged above the burner-cones, and E the top chamber, which connects the two flame-chambers D, and which has its top plate, e, provided

with openings e' e'', for the reception of the cooking utensils. A single flame-chamber, D, may be employed, if desired. The air-chamber B is closed on all sides, its only outlets being formed by the slots of the burner-cones c.

F represents elevated perforated air-chambers communicating at their lower ends with the air-chamber B by openings f, formed in the top plate of the latter. The air-chambers F are preferably cylindrical in form, as shown, and secured to the air-chamber B by vertical bolts g, passing through the tight top plates, f', of the air-chambers, and through the bottom plate, b', of the air-chamber B. The lower end of the cylindrical wall surrounds a collar formed on the upper side of the air-chamber B, around the opening f in the same.

The cylindrical walls of the air-chambers F are constructed of finely-perforated sheet metal, which permits the air to enter in fine jets or streams only, thereby preventing the disturbing effects on the flame, which would be caused by the sudden entrance of a large volume of air into the air-chamber B. The burners draw their supply of air from the air-chamber B by reason of the chimney action of the flame-chambers D. The air is supplied to the burners from the air-chamber B in a steady and uniform manner, thereby maintaining a steady and smokeless flame, and the air-chamber B in turn is supplied with air from the air-chambers F. The air-jets entering through the perforations of the chambers D are reduced gradually to a state of comparative quietude by passing first through the chambers D and then through the closed chamber B. The elevated air-chambers D offer a large aggregate area to the entrance of the air, and cause a copious flow of air to the air-chamber B, from which the flames are fed.

When the stove is designed for outdoor use, or for use in localities where it is exposed to strong air-currents, the air-chambers F are preferably provided with internal perforated cones, H, which depend from the top plates of the air-chambers and direct the air entering through the perforations of the outer wall toward the openings f in the air-chamber B.

I represents a removable cover applied to the rear opening, e'', and adapted to support a cooking utensil, and at the same time permit

of the escape of the products of combustion. The cover I is provided in its bottom plate with openings *i*, through which the products of combustion escape from the top chamber, E. 5 *i'* is a flange formed on the under side of the bottom plate of the cover I, to fit in the opening *e'*. The cover I is provided with an upwardly-flaring marginal flange, *i*', which prevents the wind from blowing into or across the 10 openings *i*, which would react on the flame and cause smoke.

i' are supporting studs formed on the bottom plate of the cover I, and made lower than the flange *i*', so that the bottom of the cooking utensil is below the top edge of the flange *i*'. 15

i' represents ribs formed on the inner side of the flange *i*', to form a free space around the cooking utensil for the products of combustion. This cover can be removed when 20 the oven is placed on the rear opening, *i*'.

The plates C are firmly secured to the lower ends of the flame-chambers D, and rest loosely upon the top plate, *b*, of the air-chamber B, being confined on the same by flanges *j*, formed 25 on the top plate, *b*.

k represents lugs formed on the upper side of the top plate, *b*, in front of the rear edge of the plate C, so as to limit the forward movement of the downwardly-curved edges of the 30 plate C on the top plate, *b*, of the air-chamber B. Upon turning the top portion of the stove backwardly to expose the wick-tubes, the rear edges of the plates C are held between the flange *j* and lugs *k*, and form a fulcrum on 35 which the top portion of the stove swings.

L and M are two upright bars, whereby the rear end of the top portion of the stove is supported upon the base A. The bar L is secured to the under side of the rear end of the 40 top portion, and rests with its lower end upon the upper end of the bar M, which latter is adjustably secured to the rear portion of the base A. The upper end of the lower bar, M, is provided with a socket, *m*, having an inclined bottom, whereby the lower end of the 45 upper bar, L, is held firmly in place. The lower bar, M, is attached to the base A by a slotted foot, N, and screw *n*, in such manner that it can be moved backwardly and forwardly on the base. Upon moving the bar M backwardly to the position represented in Fig. 1, the bar M supports the bar L and the top of 50 the stove in its normal position. Upon moving the bar M forwardly the bar L drops down until it rests on the base A, as indicated in 55 dotted lines in Fig. 1, and the top portion of the stove turns on the rear edge of the plate C, which is confined between the flange *j* and lug *k*, thereby exposing the upper ends of the 60 wick-tubes.

I do not intend to claim anything in this application which is claimed in my pending application, No. 114,053, filed December 10, 1883.

65 I am aware that perforated plates and perforated tubes have been used in various ways

for supplying air to a flame, and I do not broadly claim such parts; but

I claim as my invention—

1. The combination, in a lamp-stove, of a 70 wick-burner and burner-cone, a closed air-chamber arranged below the burner and communicating with the under side of the burner-cone and supplying air thereto, and an elevated perforated air-chamber adapted to contain a body of air, and which surmounts the air-inlet opening of the closed air-chamber, and permits the entrance of air only through its perforations, substantially as set forth.

2. The combination, in a lamp-stove, of a 80 wick-burner and burner-cone, a closed air-chamber communicating with the under side of the burner-cone and supplying air thereto, a perforated air-chamber which surmounts the air-inlet opening of the closed air-chamber 85 and permits the entrance of air only through its perforations, and a deflector arranged within said perforated air-chamber, and adapted to direct the air toward the air-inlet opening of the closed air-chamber, substantially as set 90 forth.

3. The combination, with a wick-burner, *a*, and burner-cone *c*, of the closed air-chamber B, having an air-inlet opening, *f*, a perforated chamber, F, provided with a top plate, *f'*, 95 and a bolt, *g*, whereby the chamber F is secured to the chamber B, substantially as set forth.

4. The combination, with the flame-chamber D, having a flanged bottom plate, C, of 100 the air-chamber B, provided on its upper side with a flange, *j*, and lug *k*, between which the rear edge of the flanged bottom plate, C, is confined, substantially as set forth.

5. The combination, with the base and the 105 movable top portion of a lamp-stove, of supporting-bars secured, respectively, to the base and top portion, and made adjustable with reference to each other, whereby the rear end of the top portion of the stove is supported 110 in its normal position when the supporting-bars are engaged with each other, and permitted to drop when said bars are disconnected, substantially as set forth.

6. The combination, with the base and the 115 movable top portion of a lamp-stove, of a supporting-bar, L, secured to the top portion, and a supporting-bar, M, attached adjustably to the base, substantially as set forth.

7. The combination, with the base and the 120 movable top portion of a lamp-stove, of a supporting-bar, L, secured to the top portion, and a supporting-bar, M, provided with a slotted foot, N, attached to the base by a screw, 125 *n*, and a socket, *m*, in which the lower end of the bar L is held, substantially as set forth.

Witness my hand this 1st day of February, 1884.

CHARLES T. HAM.
